PORTABLE POWER HAMMER

Alenzo G. Decker, Jr., Towson, Md., assignor to
The Black and Decker Manufacturing Company,
a corporation of Maryland

Application July 21, 1939, Serial No. 285,681

16 Claims. (Cl. 125—33)

The present invention relates to a hand directed, supported and controlled power hammer of the general type shown in Baker Patent No. 2,013,296. This is operated by an electric motor enclosed within the tool casing, but various features of the invention are capable of application to portable hammers operated from other sources of power. While the ram in this type of hammer is operated by a crank and connecting rod, it is dependent for the storage of energy at each stroke upon a spring which is either a coiled spring or a pneumatic spring or a combination of coil and pneumatic spring, to increase at the proper instance, the impact incident to the normal reciprocation by means of crank and connecting rod.

The improvement of the present invention relates particularly to the means for storing and delivering this excess impact avoiding certain defects which have come to be recognized as of importance.

In accordance with previous development in this art, the spring was concentrically loaded and for this purpose was provided with closed coils at each end and there was sufficient clearance between the outer surface of the piston body and the active coils which intervene between the closed coils at the ends to eliminate wear. Outstanding defects of this design were found to be that the spring would break due to wear adjacent the ends of the closed coils and due to concentration of stress at these points and a further defect was due to the fact that the unsupported end or ends of this spring were of sufficient weight to cause surging or vibration due to the inertia of these parts of the spring made effective by the rapid reciprocation. Surging results in excess stresses which also cause spring failure, also there was a tendency to break at the point between the closed coils where the springs were rigidly supported and the free portions where they were not so supported.

The present invention provides a new spring arrangement and a new spring in which the closed coils at the end or ends have been eliminated resulting in a spring which must be loaded eccentrically and which to avoid lateral bending is supported throughout its entire length, this support is also of great benefit in that it provides a dampening action which not only eliminates the effect of the weight and the inertia of the spring during reciprocation but by its dampening action it reduces or eliminates surging above referred to and it also has the effect of reducing

the tendency to concentrate the stress adjacent the ends where the closed coils occurred.

The invention also provides means for connecting the ram to the cross head comprising a hollow ram which serves as a cylinder which receives the shank of a steel piston which is made hollow and of an enlarged diameter to provide a frictional support for the spring throughout its length. This construction is economical to manufacture and increases the life of the piston on account of the feasibility of constructing it of steel and permits a large diameter piston shank for a given diameter of spring which in turn increases the available size of the compression chamber which connects the ram to the cross head thus improving the hammer action. Other telescoping members may be substituted for the cylinder and piston.

In accordance with an alternative construction which has considerable advantages, a steel sleeve is pressed on to an aluminum or similar light metal piston, which sleeve serves as a support for the spring and the steel ram is trepanned providing for the compression of the spring without causing the supporting sleeve to strike the ram.

In these constructions it has been found that due partly to the increase in the size of the piston shank and consequently the size of the compression chamber, the ram tends to continue its motion and to strike blows on the nose of the hammer when the drill bit has been removed. To overcome this tendency means has been provided to catch the ram and hold it long enough to throw it out of synchronism with the cross head thereby reducing or preventing the recoil of the ram and thus stopping the hammer action. Two forms of ram checking means are shown.

In the accompanying drawings, I have illustrated so much of a portable power driven hammer as is necessary to a full comprehension of the invention in its various forms and of the manner of constructing, applying, operating and using the same.

45 In the drawings:

Fig. 1 is a longitudinal section on a plane of the axis of the hammer barrel and guide.

Fig. 2 is a section on the line 2—2 in Fig. 1.

Fig. 3 is a top plan view of the friction or expansion sleeve or spring ring shown in Fig. 1.

Fig. 4 is a side elevation, broken away to show a portion of the ring in section.

Fig. 5 is an elevation of the upper or handle end of the tool showing the motor casing and the upper end of the barrel above the line 2—2 in

Fig. 1, the internal construction being shown in broken lines.

Fig. 6 is a section showing a modified construction, the view being a section on a plane of the barrel axis, corresponding to Fig. 1.

Fig. 7 is a section on the line 7—7 in Fig. 6.

Fig. 8 is an external elevation of a hammer of this type shown on a reduced scale.

Fig. 9 is a fragmentary section on a plane of the barrel axis showing a modified form of friction ring for checking the motion of the ram to throw it out of synchronization.

Fig. 10 is a section on the line 10—10 in Fig. 9.

Fig. 11 is a view corresponding to Fig. 1, taken on the barrel axis, showing a slightly modified form of nose and spring expansion ring for checking the ram and throwing it out of synchronization.

Fig. 12 is a section on the line 12—12 in Fig. 11.

Fig. 13 is an enlarged view in the nature of a fragmentary section on the barrel axis, showing the lower end of the ram in contact with the nose, the construction corresponding to that of Fig. 11.

Referring to the drawings by numerals and having particular reference to Figs. 1, 2, 5 and 8, the portable hammer in the form shown comprises a barrel 1, which is formed at its upper end with a crank case 2, and gear case 3, which are parts of the outer casing which also includes field casing 4, and brush housing or casing 5. The gear casing and the field casing are shown as detachable and the brush housing in the form shown is integral with the field casing. The illustration also includes a handle or grip 6 attached to the crank case and to the field casing, the handle or grip in the form shown being provided with a switch operating trigger 7, and a cord protector 8 enclosing the inner end of the cable 9.

In the form illustrated in Fig. 5, an electric motor 10 is enclosed within the field casing. The motor 10 is provided with a cooling fan 11, and connected by gears 12, to and with a crank 14 and crank pin 15 which operates a connecting rod 16 which reciprocates a cross head 17, to which it is connected by wrist pin 18, the cross head having a suitable guide 19 which in the form shown in Fig. 1 is integral with the ram guide 20 and somewhat larger in cross section. The term cross head is, however, not strictly limited to a crank operated member similar reciprocation being otherwise obtainable. The arrangement above defined is known practice capable of wide variation and not essential to the invention.

Referring particularly to Figs. 1 and 2, the barrel 1 is provided with a nose 21 at its lower end which in the form shown is threaded into the lower end of the barrel and provided with a bit socket or guide 22 which is aligned with the axis of the barrel.

The ram guide 20 which is a metal tube in accord with the existing practice is threaded or otherwise secured at its ends at 24 and 25 within the barrel which provides a jacket 26 or cooling space about the guide and said jacket is ventilated at 27. The ram 30 is connected to the cross head 17 by means of a cylinder and piston. In the construction shown in Fig. 1, the cylinder 31 is formed integral with the ram or vice versa and the cylinder and ram have slotted portions 33 and 34 which have a sliding fit in the guide 20 and provide for venting the space beneath the ram, and the cross head is

similarly vented at 35 to avoid impounding air within the barrel.

The operation of the parts thus described is more fully explained in the above cited patent.

5 The cross head 17 has formed integral therewith a piston 36 which controls a suitable compression space 32 within the cylinder 31 and a spring 38 is compressed between the cylinder 31 and the cross head 17, whereby energy is stored in the spring and by compression beneath the piston 36 to be released in synchronism with the normal reciprocation of the cross head as in the above cited patent. The action of the cylinder and piston providing alternate compression and 10 vacuum at 32 combined with the action of spring 38 provides a resilient means between the cross head and ram whereby motion is transmitted to the cross head from the ram and the ram is vibrated relatively to the cross head as the latter reciprocates. The spring 38 as shown is secured at its upper end in groove 39 formed in an enlarged portion 40 at the upper end of the piston. The spring 38 which is of helical form terminates in a helically arranged end portion 41 15 which bears against the lower surface of the cross head 17 and has its operative portion 42 frictionally engaged with the enlarged barrel 36' of piston 36 which is hollow at 37 to provide reduced weight with sufficient diameter to engage 20 the spring whereby the spring is permitted to contract and expand but is frictionally engaged for purposes of dampening. The lower end of this spring 38 at 43 is helically arranged and at its extreme end 43' bears against the top surface of the cylinder 31, the spring being secured at its opposite end 41.

25 It will be noted that the spring is thus loaded eccentrically at 41 and 43' where it contacts the cross head and cylinder and is supported throughout its entire length frictionally by contact with the outer surface 38' of the piston 36 between the enlarged portion 40 of the piston which is grooved at 39 to engage the spring and the lower end of the spring at 43', and the frictionally engaged portion 42 moves along the piston as the spring contracts and expands and the cylinder and piston move one relatively to the other.

30 The frictional supporting function prevents lateral bending of the spring, i. e., the bending of the spring to one side as the load is applied and also prevents surging of the spring giving what may be termed a dampening action eliminating the effect of weight of the spring particularly the closed coil formerly employed. This method also avoids the concentration of stress due to having the ends of these springs in closed coils for loading purposes. It will also be noted that the shank of the piston 36 is hollowed out to reduce its weight permitting it to be made of sufficient size to support the spring frictionally. This method of construction provides for economical manufacture and increases the life of the piston and permits it to be made of hard metal as steel instead of the lighter metals and that it increases the size of the compression chamber which improves the action of the ram.

35 It has been found, due to the increased size of the piston or piston shank and the consequent increased size of the compression chamber, the ram has a tendency to continue to strike blows on the nose 21 of the hammer after the drill bit has been removed. To overcome this tendency means has been provided in the path of

the ram beyond its normal stroke but within the stroke which is performed in the absence of a bit, said means being adapted to check or prevent the recoil of the ram as it passes beyond its normal stroke. By merely checking the recoil of the ram, it is thrown out of synchronization with the vibrations of the spring and the motion of the cross head, the hammering action of the ram, in idling, being thus either prevented or so reduced that it becomes harmless.

For this purpose, in the form of the invention now being discussed an expanding sleeve 48 has been provided as shown in Figs. 1, 3 and 4, and this sleeve 48 which is also referred to as a ring, is divided into six segments 49 by six slots 49' which as shown are parallel to the axis and extend downwardly from the top edge 49'' to a portion 50 at the lower end which is thickened and threaded internally and externally at 50' and 50'' respectively, the internal threads 50' in the form shown engage the nose and the external thread engages the inside of the ram guide near the end whereby the ring is turned down against suitable packing at 51, provided on a peripheral upturned shoulder 52 on the nose 21, the nose in turn having a threaded engagement at 53 with the inner surface of the lower end of the barrel 1.

The sleeve or ring 48 is shown as internally tapered at its upper end at 54 being thus adapted to engage the lower end of the ram 30 which is correspondingly tapered at 55, the internal diameter of the sleeve or ring 48 being slightly less than the external diameter of the ram, thus when the bit or star drill is removed the ram moves forward or downwardly it is forced into the expanding sleeve or ring 48 and held by the sleeve long enough to throw the ram out of synchronization with the piston and cross head 17 thus checking the tendency of the ram to build up hammer action due to the combined synchronized action of the spring and vacuum in the chamber 37 with the cross head motion which synchronized action is explained in the prior patent above cited.

Figs. 6 and 7 illustrate a modified form of the construction in which the ram 60 is formed with an upwardly extending piston 61 which fits in a cylinder 62 formed in a cylinder casting 65 carried by and attached to the cross head 63, being in this instance formed integrally with the cross head which fits and slides in the ram guide 59.

In this case a steel sleeve 64 is pressed onto and outside of the outer surface of the cylinder casting 65 which for lightness is of aluminum and the head of the ram is trepanned or grooved circumferentially about the base of the piston at 66; providing for the entrance of the end of the sleeve 64, into this groove so that the spring 67 can be compressed between the ram and the cross head without causing the sleeve to strike the head of the ram, said head being indicated by reference character 68. The groove 66 which extends circumferentially around the base of the piston 61 is parallel to the axis extending downwardly in a direction away from the cross head 63.

The sleeve 64 serves as a guide and as a damper for the spring 67 which corresponds to the spring 38 in Fig. 1. The outer surface of sleeve 64 serving the purpose of the outer surface of the piston 36 in Fig. 2, i. e., as a guide for an eccentrically loaded spring and as a damper to prevent surging.

It will be noted that the cylinder 62 is provided with vents 69 and 70 to limit the pressure and vacuum and the ram head 68 is grooved at 71 to

prevent accumulation of back pressure beneath the ram.

This is a highly satisfactory construction as to the details described, though the construction first described is preferred as capable of production on a large scale at a relatively small cost.

Figs. 9 and 10 illustrate a modified form of friction or expansion ring corresponding to the ring 48 in Figs. 1, 3 and 4. These figures show a ram head 75 of the hollow type in a ram guide 73, which is grooved internally at 76, the groove 76 being substantially parallel to a plane at right angles to the axis of the tool, this groove contains a spring wire hexagonal ring 77 which is of an internal diameter a little less than the external diameter of the ram head 75, so that the ram head may expand the ring, as to the centers of its hexagonal sides 79 as it advances toward the nose 81 when the bit is displaced. The spring ring is to prevent hammering of the ram on the nose when the bit is removed and consequent injury to the tool.

It will be noted that the ram head 75 is shown as circumferentially grooved as to its outer surface at 80 which provides a seat and grip for the ring 76 as the groove 80 passes said ring, usually engaging on the up stroke.

As previously noted in connection with the member 48 in Figs. 1, 3 and 4 the purpose of this construction is to check the recoil of the ram due to the spring and/or vacuum and pressure in the cylinder, etc., and to either hold it in depressed position or to throw it out of synchronization with the reciprocations of the cross head thus reducing in the absence of a bit in operative engagement with the work, the energy imparted to the ram on its descent. At other times the ram is stopped by the bit near the position shown in Fig. 1 so that the friction expanding sleeve or ring 48 or 76 is non-essential under such circumstances; i. e., when the bit is in place and pressed against the work, and has no effect. When the bit is removed, however, the ram advances to or approaches the position shown in Fig. 9, groove 80 passing ring 76 and on its return stroke the friction or expansion ring 76 becomes effective to throw the vibrations of the ram due to the spring 67 or 38 and/or the cylinder and piston action out of synchronization with the reciprocations due to the action of the crank and cross head reducing the stroke of the ram and the power of the same so that it does not advance into contact with the nose 81.

Figs. 6, 9 and 10 show vents 82 near the lower end of the barrel, providing a passage for the ventilating air to cool the guide and ram adjacent the point of impact.

Referring now to Figs. 11, 12 and 13, Fig. 11 resembles Fig. 1 except as to the type of friction expansion sleeve or ring 48 in Fig. 1, for checking the recoil of the ram.

Figs. 11, 12 and 13 show the ram guide 20 grooved circumferentially at 83 near its lower end, the groove being parallel to a plane at right angles to the tool axis. The barrel is indicated by reference character 1 and the ram guide by reference character 20.

The groove 83 receives the spring expansion ring 84 which in this instance is in the form of three relatively flat arcs 85 meeting at their ends at continuous corner portions 85', these corners 85' are deeply seated in the groove 83, the middle portion of the arcs 85 projecting from the groove into the guide space to be engaged by the head 86 of the ram as it approaches the nose 87 on

the down stroke, the bit being withdrawn from the socket 88 so that there is no resistance to the advance of the ram.

The ram head in these figures is shown as grooved at 89 circumferentially and at right angles to the axis, the walls of the groove being inclined as to the side of the groove toward the upper end of the guide or cylinder 20 and more abrupt on its lower side at 90 which provides for a convenient engagement of the spring ring or expansion ring 85 by said groove 89 as the ram head 86 passes it. In case the bit 82 is withdrawn engagement of the piston takes place normally on the return stroke. The effect being that the delivery of the energy stored by compression in the spring and/or in the cylinder is thrown out of synchronization with the normal reciprocation of the cross head reducing the stroke and avoiding hammering action off the ram head on the nose 87 which would otherwise take place when the bit is withdrawn.

The term cross head as used herein includes any reciprocating member operating the ram through and by way of a resilient element and the term spring includes any resilient means serving a similar purpose.

The improved operation and the advantages resulting from the new constructions above disclosed have been fully described and discussed in the preamble and in connection with the details of the drawings.

The preferred and several modified forms of the invention and the manner of constructing, applying, operating and using the same in connection with a power driven hammer whereby these advantages accrue having been thus described specifically and in detail in order that the manner of constructing, applying, operating and using the invention may be fully understood, the specific terms are used descriptively rather than in a limiting sense the construction shown being capable of wide variation within the spirit of the invention.

What I claim and desire to secure by Letters Patent is:

1. In a hand controlled and supported power operated hammer of the type described having a reciprocating cross head and a ram and cooperating cylinder and piston members connecting the cross head and ram, the piston being hollow, and a spring coiled about and having a frictional engagement with one of said members for a substantial portion of its length, said spring being in pressure transmitting relation at one end with the cross head and at the other end with the ram, said frictional engagement serving to dampen the action of the spring and prevent surging, and ram checking means below the normal stroke of the ram to check the recoil of the ram when the hammer is idling in the absence of a bit.

2. In a hand controlled and supported power operated hammer of the type described having a reciprocating cross head and a ram and ram guide with cylinder and piston members between the cross head and ram, the piston being hollow, a coiled spring encircling one of said members which is of the largest diameter permitted by the guide, the spring having frictional engagement with said member substantially throughout the entire length of the spring and bearing at one end against the cross head and at the other end against the ram and tending to advance the ram, said spring being eccentrically loaded, said frictional engagement serving to dampen the ac-

tion of the spring and prevent surging and to support the spring against lateral yielding.

3. In a hand controlled and supported power operated hammer of the type described having a reciprocating cross head and a ram with telescoping members between the cross head and ram, a substantially helical spring encircling one of said members and having frictional engagement therewith, and adapted to apply pressure at one end against the cross head and at the other end against the ram and tending to advance the ram, said frictional engagement extending substantially throughout the length of the spring between its bearing on the cross head and the bearing on the ram, and serving to dampen the action of the spring and prevent surging, the spring being eccentrically loaded and said frictional contact also serving to prevent lateral yielding of the spring.

4. A power operated hammer of the reciprocating type having a reciprocating cross head and a ram and telescoping members and resilient means connecting the cross head to the ram to vibrate the ram relatively to the cross head and by synchronization to accentuate the blows due to the reciprocation of the cross head, ram checking means in the path of the ram operating beyond the end of the normal stroke of the ram to check the recoil of the ram when the tool is idling in the absence of a bit whereby harmful hammering in idling is prevented by stopping the ram or throwing it out of synchronization with the spring and cross head.

5. A power operated hammer of the reciprocating type having a reciprocating cross head and a ram and telescoping members and a spring cooperating therewith to transmit pressure from the cross head to the ram to vibrate the ram relatively to the cross head and by synchronization to accentuate the blows due to the reciprocation of the cross head, friction means in the path of the ram located beyond the end of the normal stroke of the ram to check the rebound of the ram when the tool is idling, said friction means being rigidly engaged with a stationary portion of the hammer.

6. A power operated hammer of the reciprocating type having a reciprocating cross head and a ram and telescoping members and a spring cooperating therewith to connect the cross head to the ram to vibrate the ram relatively to the cross head and by synchronization to accentuate the blows due to the reciprocation of the cross head, friction means in the path of the ram, operating beyond the end of the normal stroke of the ram to throw the vibrations of the ram due to the spring action out of synchronization with the reciprocations of the cross head when the ram is idling, said friction means being in the form of a ring in the path of the ram and rigidly engaged with a stationary portion of the hammer, the upper portion of said ring being tapered and the ring being of slightly less internal diameter than the external diameter of the ram and having slots extending downwardly from its upper edge to provide for yielding to permit the entrance of the ram into the ring.

7. A power operated hammer of the reciprocating type having a positively operated cross head and a ram and telescoping members and a spring cooperating therewith to connect the cross head to the ram to vibrate the ram relatively to the cross head and by synchronization to accentuate the blows due to the reciprocation of the ram, friction means in the path of the

ram located beyond the end of the normal stroke of the ram to throw the vibrations of the ram due to the spring action out of synchronization with the reciprocations of the cross head when the ram is idling, said friction means being in the form of a spring ring of less internal diameter than the outside diameter of the ram near its lower end said ring encircling the path of the ram beyond its normal path and being seated in a stationary portion of the tool.

8. A power operated hammer of the reciprocating type having a cross head and a ram, a ram guide and cylinder and piston members connecting the cross head to the ram the piston being hollow, a spring coiled about one of said members to vibrate the ram relatively to the cross head in synchronization with the motion of the cross head and accentuate the blows due to the reciprocation of the cross head the spring being in frictional engagement with said member substantially throughout its length said member being of the largest diameter which the guide will admit and a ram checking device operating on the ram when it moves beyond its normal stroke, said checking device serving to check the recoil of the ram when the hammer is idling in the absence of a bit.

9. A power operated hammer having a cross head, a ram and telescoping members and a spring connecting the ram to the cross head and tending to advance the ram, the spring being coiled about one of said members in frictional sliding engagement therewith substantially throughout its length and secured thereto at one end and having its other end open and inclined and bearing against the other said member at its extremity only.

10. In a power hammer of the type described having a cross head, a ram and cylinder and piston members and a spring connecting the cross head and ram to set up vibration of the ram relatively to the cross head, one of said members being provided with a jacket overlapping the other said member, the spring being coiled about said jacket and frictionally engaged therewith intermediately of and for a substantial proportion of the length of the spring.

11. In a power hammer of the type described having a cross head, a ram and cylinder and piston members and a spring connecting the cross head and ram to set up vibration of the ram relatively to the cross head, one of said members being of light metal provided with a hard metal jacket overlapping the other said member, the spring being coiled about said jacket and frictionally engaged therewith intermediately of and for a substantial proportion of the length of the spring one of said members being grooved in line with the jacket to admit the end of the jacket when the spring is approaching full compression.

12. In a power hammer of the type described having a cross head and a ram and cylinder and piston members and a spring connecting the cross

head and ram to set up vibration of the ram relatively to the cross head, one of said members being of light metal with a hard metal jacket, the spring being coiled about said jacket and frictionally engaged therewith intermediately of and for a substantial proportion of the length of the spring.

13. In a hand controlled and supported power operated hammer having two reciprocating members comprising a cross head and a ram and a coiled spring in pressure transmitting relation at one end with the cross head and at the other end with the ram and tending to advance the ram, and means having telescoping engagement with one of said members and having frictional engagement with the coils of the spring substantially throughout the length of the spring, said frictional engagement serving to dampen the action of the spring and prevent surging.

14. In a hand controlled and supported power operated hammer having a reciprocating cross head and a ram with telescoping guiding means therefor, a substantially helical spring transmitting pressure from the cross head to the ram and tending to advance the ram with the cross head, said spring having a frictional engagement with one of said telescoping members throughout its length serving to dampen the action of the spring and prevent surging, the spring being eccentrically loaded and said frictional contact also serving to guide and prevent lateral yielding of the spring.

15. In a hand controlled and supported power operated hammer, having a positively operated reciprocating cross head, a ram with resilient means between the ram and the cross head and ram checking means in the path of the ram, said resilient means transmitting the motion from the cross head to the ram and permitting vibration of the ram relatively to the cross head, said checking means being inoperative within the normal stroke of the ram, but engaging the ram when it moves beyond its normal working stroke as in idling in the absence of a bit.

16. A power operated hammer of the reciprocating type having a positively operated cross head and a ram, and resilient means between the cross-head and the ram to reciprocate the ram and permit vibration of the ram relatively to the cross head as the latter reciprocates and to accentuate the blows due to the reciprocation of the cross head, means in the path of the ram located beyond the end of the normal stroke of the ram, said latter means being in the form of a spring ring of less internal diameter than the outside diameter of the ram near its lower end, said ring encircling the path of the ram near the lower end of its stroke and means securing the ring in a stationary portion of the tool, said ring being adapted to be entered by the lower end of the ram and to grip the ram when it passes beyond its normal stroke.

ALONZO G. DECKER, JR.
